UNITED STATES PATENT OFFICE.

CHARLES BRISTOW, OF CHRISTCHURCH, NEW ZEALAND.

MACHINE FOR FORMING PLASTIC MATERIAL INTO LUMPS.

No. 833,576.

Specification of Letters Patent.

Patented Oct. 16, 1906.

Application filed May 31, 1906. Serial No. 319,517.

To all whom it may concern:

Be it known that I, CHARLES BRISTOW, a subject of the King of Great Britain, and a resident of Christchurch, in the district of 5 Canterbury, New Zealand, have invented a new and Improved Machine for Forming Plastic Material into Lumps, of which the following is a full, clear, and exact description.

The object of the invention is to provide a new and improved machine for forming butter and other plastic material into lumps ready for table use, the machine being more especially designed for use in restaurants, hotels, and like establishments and arranged 15 to permit an operator to quickly and conveniently form lumps of any desired shape in a very convenient and sanitary manner and without much physical exertion on the part of the operator.

20 The invention consists of novel features and parts and combinations of the same, which will be more fully described herein-after and then pointed out in the claims.

A practical embodiment of the invention 25 is represented in the accompanying drawings, forming a part of this specification, in which similar characters of reference indicate corresponding parts in all the views.

Figure 1 is a rear side elevation of the improvement. Fig. 2 is a longitudinal sectional elevation of the same, and Fig. 3 is an enlarged transverse section of the same.

A suitably-constructed box A for containing the butter or other plastic material is preferably mounted on a clamp B for conveniently securing the machine to a table or other support. The box A is provided on top with a hinged cover A' for conveniently placing the plastic material into the box, the 35 cover having suitable fastening devices for locking the cover in place after the material is placed in the box. On the front end of the box A is formed an aperture A², registering with a nozzle C of any desired shape and removably held in a suitable guideway D, arranged on the outer face of the front of the box A. Within the box is arranged a plunger E for pressing the plastic material forward through the opening A² into and through 40 the nozzle C, so as to give a desired shape to the material forced out of the nozzle C and corresponding to the shape of the nozzle.

The plunger E is provided with a rack-bar E', extending rearwardly through an opening A³ in the rear end of the box A, and the

said rack-bar E' is mounted to slide in a suitable guideway E², attached to the rear end of the box at the outer face thereof. A pinion F' is in mesh with the rack-bar E' and is secured on a transversely-extending shaft F, 60 journaled in suitable bearings carried on the box A, and on the said shaft F is arranged a handle F² under the control of the operator for turning the shaft F to cause the pinion F' to impart a sliding motion to the rack-bar E' with a view to force the plunger E forward for pressing the material out through the nozzle C, as before explained. As the material issues through the nozzle C it is cut by a cutter G, preferably in the form of a wire attached 65 to a handle H, under the control of the operator and secured on a shaft I, journaled in suitable bearings I', attached to the rear side of the box A. The cutter G when swung downward passes in close proximity to the 70 outer end of the nozzle C to cut the material pressed through the nozzle into a small lump, and when the cutter G returns to an uppermost position then it travels in a plane a distance from the front end of the nozzle C, so 75 as to prevent the cutter during the return or upward stroke from coming in contact with the plastic material at the outer end of the nozzle C. In order to obtain this result, a longitudinal sliding motion is given to the 80 shaft I, and for this purpose a cam-arm J is secured by a set-screw J' on the shaft I, and the free beveled end J² of the cam-arm J rests against a cam K, fulcrumed at its lower end at K' on the bearing I', previously mentioned. 85 A spring L presses the cam K to normally hold the latter in an outermost position, as shown in Fig. 3, to hold the cutter G in an uppermost position, the outward-swinging motion of the cam K being limited by a stop-arm K², projecting from the cam K and adapted to abut against a shoulder I², arranged on the bearing I'. 90 95

The cam K is provided at its front face with cam-faces K³ and K⁴, adapted to be alternately engaged by the beveled end J² of the cam-arm J, so that when the handle H is swung downward, and with it the cutter G, and the shaft I is turned then the cutter G swings close to the outer end of the nozzle C, 100 and when the cutter G has passed the nozzle then the beveled end J² moves in contact with the cam-face K⁴, so that the shaft I is shifted forwardly in the direction of its length. When the operator releases the 105 110

handle H, then the spring L, pressing against the cam K in contact with the arm J, causes a return turning movement of the shaft I, and consequently of the handle H and the cutter G; but during this return movement the cutter G travels in a plane a distance from the front end of the nozzle C. When the cutter G moves into an uppermost position, then the end J² of the arm J engages the cam-face K², so that the arm J and the shaft I, together with the handle H and the cutter G, are shifted rearwardly to bring the cutter G back to its starting position and into a transverse vertical plane extending close to the front end of the nozzle C. The return swinging motion of the shaft I is limited by a stop-arm J³, engaging the bearing I', as plainly indicated in Fig. 3.

The operation is as follows: When the plunger E is in a rearmost position, then the box is filled with the plastic material, after which the cover A' is closed and locked, and then the operator turns the handle F², so as to move the plunger E forward with a view to press the plastic material out through the nozzle C. When the plastic material has been forced a desired distance out of the nozzle C, then the operator swings the handle H downward for the cutter G to cut off the material in front of the nozzle C to form a small lump of the desired thickness and of a shape corresponding to that of the nozzle. When the operator releases the pressure on the handle H, then the cutter G returns in a different plane, as previously explained, to prevent the cutter from coming in contact with the plastic material during the return stroke.

The machine is very simple and durable in construction and is composed of comparatively few parts not liable to get easily out of order.

Having thus described my invention, I claim as new and desire to secure by Letters Patent—

1. A machine for forming plastic material into lumps, comprising a box for containing the material, a nozzle at one end of the box, a plunger movable in the said box to force the material out of the nozzle, a cutter mounted to swing in front of the said nozzle,

and means for moving the cutter in different planes on the down and return strokes.

2. A machine for forming plastic material into lumps, comprising a box for containing the material, a nozzle at one end of the box, a plunger movable in the said box to force the material out of the nozzle, a cutter adapted to move down and up in front of the said nozzle, a shaft carrying the said cutter, and means for shifting the shaft in the direction of its length. 55

3. A machine for forming plastic material into lumps, comprising a box for containing the material, a nozzle at one end of the box, a plunger movable in the said box to force the material out of the nozzle, a cutter adapted to move down and up in front of the said nozzle, a shaft carrying the said cutter, a cam-arm on the said shaft, and a cam device engaged by the said cam-arm for shifting the 70 shaft in the direction of its length. 65

4. A machine for forming plastic material into lumps, comprising a box for containing the material, a nozzle at one end of the box, a plunger movable in the said box to force 75 the material out of the nozzle, a cutter adapted to move down and up in front of the said nozzle, a shaft carrying the said cutter, a cam-arm on the said shaft, and a spring-pressed pivoted cam having two cam-faces for alternate engagement by the said arm. 8c

5. A machine for forming plastic material into lumps, comprising a box for containing the material, a nozzle at one end of the box, a plunger movable in the said box to force 85 the material out of the nozzle, a cutter adapted to move down and up in front of the said nozzle, a shaft carrying the said cutter, a cam-arm on the said shaft, a spring-pressed pivoted cam having two cam-faces for alternate engagement by the said arm, and a stop-arm on the said shaft to limit the downward-swinging motion of the said cutter. 90

In testimony whereof I have signed my name to this specification in the presence of 95 two subscribing witnesses.

CHARLES BRISTOW.
